UNITED STATES PATENT OFFICE

101,352

DESIGN FOR A TEXTILE FABRIC OR SIMILAR ARTICLE OF MANUFACTURE

John F. Gaul, Jr., Clifton, N. J., assignor to Botany Worsted Mills, Passaic, N. J., a corporation of New Jersey

Application June 19, 1936, Serial No. 63,397

Term of patent 14 years

To all whom it may concern:

Be it known that I, John F. Gaul, Jr., a citizen of the United States of America, residing at No. 1110 Van Houten Avenue, in the town of Clifton, State of New Jersey, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The repeat unit is indicated by the area between the parallel broken lines on the drawing.

The characteristic feature of the design resides in the arrangement of thickened threads of substantially the same lengths in pairs of such lengths as to form raised components of stripes extending vertically of the fabric, the groups of thickened threads, formed by such pairs of threads being spaced from each other, by substantially equal vertical spaces.

I claim:

The ornamental design for a textile fabric or similar article of manufacture substantially as shown and described.

JOHN F. GAUL, JR.
